UNITED STATES PATENT OFFICE

2,502,945

CENTRIFUGAL SEPARATOR

Tore Verner Hanno, Stora Essingen, Sweden, assignor to Aktiebolaget Separator, Stockholm, Sweden, a corporation of Sweden

**Application January 8, 1946, Serial No. 639,732
In Sweden January 22, 1945**

4 Claims. (CL. 233—22)

1

For the removal of yeast cells, remaining after the fermentation, from beer, centrifugal separators are now employed. The yeast cells, which are heavier than the beer, deposit under the influence of the centrifugal force in the sludge space of the centrifugal bowl, and are maintained there till the centrifuge has been stopped. Thus beer freed from yeast cells is discharged through the outlet of the centrifuge. For the separation of the yeast cells there are generally used hermetically closed centrifuges, but so-called paring disc centrifuges could also be used.

After the centrifuge is stopped it is usually flushed clean by connecting its inlet to a water supply pipe and feeding water through it. At the same time an outlet, provided in the pipe line between the outlet of the centrifuge and the storage tank to which the beer liberated from yeast is conducted from the centrifuge, is opened. Because the centrifugal bowl is not then rotating this known method involves the risk that such yeast cells, which have deposited in the sludge space of the bowl and are carried away with the flush water flow, may enter and remain in the discharge pipe line. When the centrifuge is next time used for treating beer these yeast cells may be carried into the storing tank for beer. As yeast cells must not be present in the finished beer the described procedure is open to serious objections.

Of course it is possible, by continuing the flushing for a very long time, e. g., for some hours, to achieve a more or less complete clean-flushing, in that the flush water removes no more yeast cells from the bowl, either because all the sludge mass containing yeast cells has been flushed out or because no more yeast cells are torn off by the flush water. This involves, however, a great waste of water and the necessity of attending to the installation long after the centrifuge has been stopped.

According to the present invention it is insured that no yeast cells shall enter the storage tank. This is effected by flowing the flush liquid backwards through the centrifuge. This is effected by connecting to the discharge pipe of the centrifuge an inlet for flush liquid, e. g. a common water supply pipe, and by providing an outlet for flush liquid at the feed inlet of the centrifuge. The direction of flow being during

2

the whole period of flushing from the outlet to the inlet of the centrifuge, no yeast cells torn off in the bowl can be conveyed into the connecting pipe between the centrifuge and the storage tank.

Fig. 1 is a diagrammatic view of a centrifugal separator installation adapted for carrying out my improved process.

Fig. 2 is a vertical sectional view through the upper part of a separator equipped with a paring disc and in which my improved process is adapted to be practiced, the separator being the same as the separator forming part of the installation shown in Fig. 1.

Fig. 3 is a view similar to Fig. 1 but showing an installation having a separator of the aforementioned hermetically closed type, in place of a separator equipped with paring discs.

Referring first to Fig. 3:

20 Beer, containing yeast cells, is, by means of a centrifugal pump 2, carried from a tank 1 through a centrifuge 3 to a storing tank or a so-called pressure tank 4 for beer freed from yeast cells.

25 To the feed pipe 5a between the pump 2 and the centrifuge 3 is connected an outlet pipe 6, which is shut off during the separating operation; and to the connecting pipe 7 between the centrifuge 3 and the pressure tank 4 is connected an inlet pipe 8 for flush liquid, which is shut off during the separating operation. The pipe 8 is connected to a container for flush liquid (not shown) or to a water supply pipe.

30 During the centrifuging the beer streams from the tank 1 through the pump 2 and the pipe 5a into the centrifuge, and thence, after being freed from the yeast, through the pipe 7 into the tank 4.

35 When the centrifuging is to be interrupted a valve 9 in the pipe 5a and a valve 10 in the pipe 7 are closed. A valve 11 in the pipe 8 and a valve 12 in the pipe 6 are opened, and the flush liquid streams then in the direction of the arrows through the pipe lines and the centrifuge. Any yeast cells which are detached in the centrifugal bowl thus pass through the feed pipe 5a and thence through the outlet pipe 6. Some yeast cells may enter and adhere to the wall of the pipe 5a, but this is not objectionable. On the other hand, no detached yeast cell can enter the pipe 7. Even if the time of flushing is very short

insurance is absolute against entry of yeast cells into the pipe 7 during flushing.

In starting the centrifuge valves 9 and 10 are closed and valves 11 and 12 are opened and water is led through the centrifuge backwards, e. g., in the direction of the arrows, until the centrifuge attains its full speed. Then the valve 12 is closed and the valve 9 opened and the flow of beer begun. After the water has been driven out by the beer at the valve 11, this valve is closed, after the valve 10 has been opened. Thus there is no risk of entry of yeast cells into the pipe 7 and, in the subsequent flow of yeast-free beer, of carrying any yeast into the tank 4.

When using separators provided with so-called paring discs a mode of operation can be as follows (see Figs. 1 and 2):

When the separating has been interrupted and the beer has been driven out by the water then the water feed is interrupted. The valve 10 in pipe 7 leading from the discharge conduit 25 from the centrifuge is shut. When the separator bowl has been stopped the nut 21 is loosened. The paring disc is then pressed downwards by means of the element 22, which, acting through a ring 27 and packing ring 28, forces the parer 29 down until its lower packing ring 24 makes tight contact with the underlying bowl part, as shown in dotted lines in Fig. 2, and the packing ring 30 makes a tight joint at 23. The packing ring 31 makes a tight joint between the ring 27 and the tubular portion 32 of the discharge passage. Then water from pipe 8 and valve 11 is flushed through the discharge conduit 25 backwards through the bowl and out through the feed pipe 26. The flushing is interrupted when the water streaming out looks clean. In restarting the centrifuge the nut 21 is again tightened to the position shown in Fig. 2, thereby returning the parer 29, ring 27 and element 22 to the position shown. The valve 10 in the discharge conduit 25 is not opened until the bowl has attained its full speed. Then the valve 9 in the feed pipe is opened for feeding in the normal direction first water and then beer through the bowl.

It will be understood that in Fig. 2 the bowl inlet or feed pipe 26 is connected at the top in any suitable manner to the feed pipe 5 shown in Fig. 1, and the discharge conduit 25 is connected to the pipe 7 in Fig. 1. The parer 29 is normally in the position shown in Fig. 2, wherein the parer and the bowl outlet 33 are in communication with the atmosphere through the open space surrounding the neck of the parer. In this position of the parer, it affords communication between the interior of the centrifugal bowl shown in Fig. 2 and the discharge conduit 25 for the purified liquid, the communication to the bowl interior being to both the central zone (through the space 34 below the parer and surrounding the feed pipe 26) and the peripheral zone (through the passage 35 below the parer). The ring 27 and its packing ring 30 constitute a means operable to close communication between parer 29 and the atmosphere, by downward movement of parts 27, 30 to their dotted line positions (Fig. 2). In other words, the parts 27, 30 together with the parer form means for sealing the bowl outlet 33 (into which the parer extends) from atmosphere while providing a sealed flushing connection between discharge conduit 25 and the bowl outlet 33. This sealed flushing connection is from the annular space 36 within the stationary tubular portion 32 through the sealing ring 28 and thence through

the parer passages 29a, and it is provided independently of the space 34 between the feed pipe 26 and the surrounding bowl portion. Since the parer moves downwardly with ring 27, the lower packing ring 24 on the parer constitutes an element operable by the closing means 21 to close communication between the parer and the central zone of the bowl through space 34. That is, the lower ring 24 forms a means for sealing the space 34 between feed pipe 26 and the surrounding bowl portion, such means being movable between sealing (dotted line) and non-sealing (full line) positions for flushing and normal operation, respectively. With the parts in their lower positions, the flush liquid fed through pipes 8 and 7 and conduit 25 can pass only through parer 29, passage 35, and the peripheral zone of the bowl, and out through the feed tube 26 and pipe 5 to the discharge duct 6 for the flush liquid.

The element 22 constitutes a means operable selectively to move the sealing means, including the parts 27, 30 and the parer, between the lower or sealing position and the upper or non-sealing position, depending upon whether the bowl interior or locus of centrifugal force is to be flushed or is to be used normally for separating impurities from the liquid.

The described method of cleaning centrifugal bowls is not limited for use in the centrifugal treatment of beer, but is equally applicable to the cleaning of centrifugal bowls when, in the centrifugal purification of any liquid, solids and semi-solids are deposited in the bowl and at intervals require removal by flushing.

35 What I claim and desire to protect by Letters Patent is:

1. In a centrifuge comprising a centrifugal bowl having walls defining an outlet in communication with the atmosphere, a feed pipe for conducting a liquid into the bowl, there being a clearance space between the feed pipe and the surrounding bowl portion, and means for sealing said space and movable between sealing and non-sealing positions for flushing the bowl and for normal operation of the centrifuge, respectively, the combination of a conduit outside the bowl for communicating with said outlet independently of said clearance space and adapted to receive a bowl flushing liquid, means for sealing said outlet from the atmosphere while providing a sealed flushing connection between the conduit and said outlet independently of said space, and means operable selectively to move said last sealing means between sealing and non-sealing positions.

2. A centrifuge as defined in claim 1, in which said last sealing means includes a parer extending into said outlet and normally communicating with the conduit, the parer forming part of said flushing connection in the sealing position of said last sealing means.

3. An installation for practicing the herein described process, which comprises a supply tank, a centrifuge having a centrifugal bowl, an inlet to the bowl, a discharge conduit from the bowl, and a parer normally in communication with the atmosphere and affording communication between the bowl interior and the discharge conduit, a supply conduit connecting the supply tank and said centrifuge inlet, a storage tank connected to the discharge conduit, a device in the discharge conduit for closing the same, a duct for admitting a flushing liquid to the discharge conduit at a region between the bowl and said device, a device in the supply conduit for closing

the same, a duct for discharging flush liquid through and out of the supply conduit at a region between the bowl and said last device, and means operable to close communication between the parer and the atmosphere, to direct the flow of flushing liquid from the discharge conduit only through the bowl and thence to the supply conduit and to said discharge duct.

4. An installation according to claim 2, in which the parer is normally in open communication with both the central and the peripheral zones of the bowl, and an element operable by said means to close communication between the parer and the central zone of the bowl.
